UNITED STATES PATENT OFFICE.

LOUIS SCHLESINGER, OF NEW YORK, N. Y., ASSIGNOR OF ONE-HALF TO NATHAN D. LEVY, OF NEW YORK, N. Y.

FLASH-PAN.

1,002,763.

Specification of Letters Patent. Patented Sept. 5, 1911.

Application filed January 8, 1910, Serial No. 536,990. Renewed July 26, 1911. Serial No. 640,693.

To all whom it may concern:

Be it known that I, LOUIS SCHLESINGER, a citizen of the United States of America, residing at 1130 Union avenue, New York city, in the county and State of New York, have invented certain new and useful Improvements in Flash-Pans, of which the following is a specification.

My invention relates to flash pans used in taking so called "flash light" photographs, and refers particularly to the means for igniting the powder charge or cartridge by the light of which the picture is taken.

The principal object of the invention is to provide simple, effective and reliable means for igniting the powder charge in the pan, said means consisting preferably of a fuse plug provided with a length of suitable fusible wire, whereby the same plug may be used for an indefinite time, it being necessary merely to provide new wire to replace that used up.

A further object is to so construct the said plug that it shall be entirely self contained, and easily insertible in position, and quickly removable for examination or removal of wire.

Other objects of the invention will be disclosed in the following description thereof.

The preferred embodiment of the invention is illustrated in the accompanying drawing, wherein—

Figure 1 is a side elevational view of a flash pan constructed according to my invention. Fig. 2 is a longitudinal sectional view taken on the line 2—2 of Fig. 3, looking in the direction of the arrows; Fig. 3 is a bottom plan view of the improved flash pan; Fig. 4 is a cross sectional view thereof taken on the line 4—4 of Fig. 1 looking in the direction of the arrows; Fig. 5 is a fragmentary detail view of the contacts and associated parts employed in the flashing device; and Fig. 6 is a perspective view of the novel form of fuse plug.

Referring in detail to the figures of the accompanying drawing, the numeral 10 designates the flash pan which is preferably in the shape of an elongated comparatively narrow trough and is adapted to receive a suitable powder charge, designed to be fired by the means to be hereinafter described. The pan 10 is provided with a threaded socket 11 into which a suitable support screws, and in any desired part of the wall

of the pan, preferably in the bottom thereof, an orifice 12 is formed through which the spark for igniting the powder charge passes.

The ignition spark is preferably produced by the action of an electric current on a fuse, and the preferred arrangement for producing the spark is that about to be described.

Secured to the base of the pan 10 at approximately its median part, is an insulating plate 13 having an orifice 14 in registry with the orifice 12 in the pan. Arranged in slots or depressions in the plate 13 is a pair of metallic contact springs or tongues 15 and 16, one at each side of the orifices 12 and 14, these contact springs being held in position by insulating plates 17 and 18 spaced apart as shown and being held to the plate 13 and on the contact springs by diagonally opposite screws 19 which are preferably countersunk in the plates 17 and 18 and pass through the latter into the plate 13. The contact springs 15 and 16 are provided with binding posts 20 and 21, respectively, adapted to receive the terminals 22 and 23 of wires formed into a cable 24, and designed to convey current to the contacts from a suitable source (not shown). Overlying the plates 17 and 18 is an insulating plate 25, against which the terminals 22 and 23 are held by means of the knurled binding screws 26 adapted to thread on the posts 20 and 21.

It will be noted from the foregoing description that when the plates 13, 25 and 17 and 18 are assembled at the base of the pan 10, they form an open insulating frame, one of the plates having an orifice aligned with that in the flash pan, and the frame being so constituted as to be adapted to receive and retain the fuse plug, as more fully herein-after described.

Adapted for insertion between the plates 17 and 18 is the fuse plug clearly shown in Fig. 6 of the drawing. This plug consists of a head portion 27 and a shank or tongue 28. The head 27 is preferably formed as a sort of bobbin to receive a suitable length of wire fuse 29 which passes through the hole 30 and may be drawn across both longitudinal faces of the shank 28, one of the faces having a slot 31 formed therein, in which the free end 29a of the fuse rests. When the fuse is arranged on the plug as shown in Fig. 6, the plug may be inserted in position

between the plates 17 and 18, the wire fuse 29 traversing both contact springs 15 and 16, and the device is then ready for use.

The operation of the invention is as fol-

- 5 lows:—After a powder charge or cartridge is placed in the pan 10 the fuse plug is inserted in position and the binding screws 26 are screwed down on the terminals 22 and 23 which engage the binding posts 20 and 21 10 respectively. Current is then turned on and passes through the conducting wires to the binding posts and contact springs 15 and 16 whereby the wire fuse 29 is melted generating a spark which jumps through the orifices 12 and 14 thus igniting the charge in the pan 10.

Having thus described my invention what I claim as new and desire to secure by Letters Patent is:—

- 20 1. In a device of the character specified, the combination with a receptacle adapted to receive a powder charge and having an orifice formed in one wall thereof, of a frame of insulating material secured to said 25 receptacle and having one of its walls provided with an orifice alined with the orifice in said receptacle, and a fuse plug adapted to be inserted in said frame, said fuse plug carrying a fusible wire designed to extend 30 across the orifice in the insulating material.
2. In a device of the character specified, the combination with a receptacle adapted to receive a powder charge and having an orifice formed in one wall thereof, of a frame of insulating material secured to said 35 receptacle and having an orifice alined with the orifice in the receptacle, a contact member arranged in a groove at each side of the orifice in the frame, and a fuse plug adapted 40 to be inserted into said frame, said fuse plug carrying a fusible wire traversing the contacts and extending across the orifice in the insulating material.
3. In a device of the character specified, 45 the combination with a receptacle adapted to receive a powder charge and having an orifice formed in one wall thereof, of a frame of insulating material secured to said receptacle, said frame comprising upper and 50 lower plates, and intermediate plates spaced

away from each other, said upper plate having an orifice alined with the orifice in the receptacle, a pair of contact members carried by said upper plate, and a fuse plug adapted to be inserted between said intermediate plates, said plug carrying a fusible wire traversing said contacts and extending across the orifice in the insulating material.

4. In a device of the character specified, the combination with a receptacle adapted to receive a powder charge and having an orifice formed in one wall thereof, of a frame of insulating material secured to said receptacle and having an orifice in one wall thereof in alinement with the orifice in the receptacle, contact members carried by said insulating frame, and a fuse plug adapted to be inserted into said frame, said plug comprising a laterally enlarged head portion adapted to have spare wire coiled thereabout and a shank portion for receiving a single strand of wire designed to traverse said contacts and extend across the orifice in the insulating material.

5. In a device of the character specified, the combination with a receptacle adapted to receive a powder charge and having an orifice formed in one wall thereof, of a frame of insulating material adapted to receive the shank of a fuse plug and having an orifice in one of its walls in alinement with the orifice in the receptacle, contact members carried by said frame, and a fuse plug comprising a laterally enlarged head portion adapted to have spare wire coiled thereabout and a shank portion having a longitudinal groove on each face for receiving a single strand of wire drawn through an orifice in the plug between the head and shank portion thereof, said strand being designed to traverse said contacts and extend across the orifice in the insulating frame.

In testimony whereof I have affixed my signature in presence of two witnesses.

LOUIS SCHLESINGER.
